SHIELD FOR GUN MOUNTS

Jacob C. Jorgensen, Beverly, Mass., assignor to
 United Shoe Machinery Corporation, Flemington, N. J., a corporation of New Jersey

Application September 23, 1946, Serial No. 698,715

6 Claims. (Cl. 89—36)

1

This invention relates to gun mounts, and more particularly to shields for closing the opening in a supporting structure through which a gun projects and relative to which opening the gun is movable in azimuth and in elevation. The invention is illustrated herein as embodied in a shield for a plurality of guns mounted to project through an opening in the fuselage of an airplane, although it is to be understood that the invention is not thus limited in its application.

An object of the present invention is to provide an improved shield by which the opening in a supporting structure through which a gun projects is effectively sealed, the shield being arranged to permit movements of the gun in azimuth and in elevation without in any way obstructing the space rearwardly of the opening.

Certain types of shields which have heretofore been employed for use with airplane gun mounts are of rigid construction and are mounted to move with the gun. To maintain the opening around the gun shielded in any position of the gun the shields extend inwardly of the airplane and may be in the shape of a portion of the surface of a sphere. Upon movement of the gun to an extreme position the marginal portion of the shield moves across the opening interiorly of the airplane so that it at least partially obstructs the space rearwardly of the opening. If the gun is capable of a wide range of movement, operation of the gun may be considerably hampered by the shield when the gun is in an extreme position.

In accordance with a feature of the present invention the shield comprises a plurality of narrow plate members which are pivoted to one another about parallel axes and are movable with the gun in its swinging movements, the plate members being sufficient in number to maintain the opening completely closed in any position of the gun, there being means for guiding the excess plates at each side of the opening into folded relationship within the supporting structure.

In accordance with a further feature of the invention the plate members are formed in two sets, one at each side of the gun, the plates of each set being pivoted to one another about axes parallel to the axis of swinging movement of the gun in azimuth, there being a slide fastener closure connecting the sets of plates and a slide fastener operator surrounding the projecting gun permitting movement of the gun in elevation.

The above and other features of the invention, including various details of construction and novel combinations of parts, will now be described

2

by reference to the accompanying drawings and pointed out in the claims.

In the drawings,

Fig. 1 is a side elevation, partly in section, of a gun mount with which is associated one form of shield embodying the invention;

Fig. 2 is a plan view of the gun mount and shield with the upper portion of the shield removed and certain parts being shown in section;

Fig. 3 is a horizontal section on a larger scale than Fig. 2 of a portion of the shield and the adjacent structure of an airplane with which the mount is associated;

Fig. 4 is a plan view partly in section illustrating the means by which folding of the shield at one side of the airplane during movements of the gun in azimuth is controlled;

Fig. 5 is a section on the line V—V of Fig. 4, and Fig. 6 is a detailed view partly in section illustrating the means for connecting the adjacent ends of the sets of plates to the top and bottom supports.

The invention is illustrated as embodied in a shield for a quadruple gun mount consisting of two pairs of guns G supported one above the other and suitably carried by a yoke 10 (Figs. 1 and 2) for unitary movements in elevation. The yoke is suitably journaled about a vertical axis so that the guns may also be moved in azimuth.

The means by which the guns are supported and are moved in azimuth and in elevation form no part of the present invention and accordingly are not illustrated in detail.

The guns project through an opening in a supporting structure such as the fuselage of an airplane, the particular mount illustrated herein being intended to be carried by the tail section of an airplane. The opening is formed between side walls 12 (Fig. 2) of the airplane and top and bottom walls 14, 15, the opening in the present case being rectangular in shape. The shield for closing the opening around the guns extends outwardly of the opening and is carried by top and bottom supports 16, 18 which likewise project outwardly beyond the opening and which are journaled for movement with the yoke 10 upon movement of the guns in azimuth. The supports 16, 18 are generally dish-shaped as indicated in Fig. 1 and are connected together near

their outermost portions, when they are positioned with the guns normal to the plane of the opening, by vertical plate members 20, 22 and 24 (Fig. 2) which extend only a limited distance around the peripheries of the supports. The central plate member 22 is spaced from the plate

members 20 and 24 and the spaces are closed by flexible slide fastener closures 26 through which the guns project and with respect to which the guns move in elevation. For actuating the closures 26 upon movements of the guns in elevation, slide fastener operators 28 of conventional construction are carried by short tubes 30 through which the guns G are slid able. It will be obvious that as the guns are moved in elevation the closures 26 maintain the spaces above and below the guns, as well as between them, closed at all times and that these closures move with the guns and the top and bottom supports 16, 18 upon movement of the guns in azimuth.

For closing the remainder of the opening between the plate members 20 and 24 and the side walls 12, a plurality of narrow plate members 32 are provided which are hinged together by pintles 34 which, as illustrated in Fig. 4, are of tubular construction. Extending outwardly beyond the ends of each pintle are pins 36 (Fig. 5) each of which carries a roll arranged to be received by recesses 38 in curved plates 40 carried by the rims of the supports 16 and 18.

The plates 32 adjacent to the members 20 and 24 are detachably secured to the top and bottom supports 16 and 18 by pins 42 (Fig. 6). These pins are urged downwardly by springs 44 into apertures 46 provided by bushings 47 in the curved plates 40 adjacent to the plate members 20 and 24. In order to permit the plates 32 to be disconnected from the supporting members 16 and 18 the pins 42 may be retracted against the actions of the springs 44 and for this purpose handles 48 are connected thereto and extend inwardly of the shield so that if necessary this operation may be performed from the interior of the airplane while the airplane is in flight.

As noted in Fig. 2, the shield consists of more plates 32 than necessary at any one time to close the opening around the guns. The excess plates are received in compartments formed between the walls 12 of the airplane and inwardly extending walls 50. In order to accommodate the excess plates in the limited space available they are folded as shown in Fig. 2. Upon movement of the guns into either of their extreme positions in azimuth the excess plates will be drawn from one of the storage compartments upon turning the supports 16 and 18 and the plates are sufficient in number so that the opening around the guns remains closed in all positions of the guns.

For locking the plates 32 to the supports 16 and 18, latches 52 (Fig. 4) are provided in slots formed in the curved plates 40 between every other pair of recesses 38. These latches are pivoted to the plate 40 by pins 54 and are urged in a clockwise direction by springs 56. For a purpose which will appear as the description proceeds the rolls carried by the pins 36 projecting outwardly from the pintles 34 are alternately long and short as indicated by the reference characters 58 and 60 respectively (Fig. 5). The short rolls are engaged by the outer ends of the latches 52 which have concave roll-engaging faces 62 which cooperate with the opposite sides of the recesses 38 to maintain the short rolls in the recesses until the latches are moved by the springs 56 into the position shown at the extreme left in Fig. 4. The left ends of the latches 52 have curved faces 64 engageable with the long rolls 58 and are prevented from moving under the influence of the springs 56 during the time that the long rolls are in the recesses 38 because

of the engagement of the faces 64 with the rolls. Accordingly, as long as any one of the rolls 58 is held in its recess 38 the short roll immediately forward thereof remains locked in its recess by the associated latch 52.

In the storage compartments for the excess plates of the shield are adjustably supported guide members 66 each of which comprises tracks 68 and 70 for guiding the rolls 58 and 60 as shown most clearly in Fig. 4. The track 68 is of sufficient depth to accommodate the long rolls 58 (Fig. 5) and extends to a position slightly rearwardly of the end of the wall 12 of the airplane (Fig. 2). The track 70 is of sufficient depth to receive the short rolls 60 (Fig. 5) but is not sufficiently deep to permit entrance of the long rolls 58 thereto. Accordingly, it will be apparent that the long rolls must move into the track 68 upon movement of the supports 16 and 18 in a clockwise direction as viewed in Fig. 4. In order that the plates will fold upon each other, as shown in Fig. 4, the short rolls 60 must be prevented from passing into the deep track 68. Accordingly, provision is made for preventing movement of the latches 52 (Fig. 4) by the springs 56 as soon as the associated long roll 58 is guided out of engagement with the latch. At the junction of the tracks 68 and 70 is a partition 72 which is engaged by the outer edge of the latch 64 before that latch moves out of engagement with the outer rim of the track 68. Accordingly, the short roll is held in the recess 38 until movement of the short roll into the entranceway of the track 70 at which time the associated latch 52 is out of engagement with the partition 72. Consequently there is no danger of the short rolls leaving the supports 16, 18 prematurely and moving into the track 68. Movement of the latch 52 by the spring 56 is limited by a pin 74 passing through an aperture 75 in the latch.

Upon movement of the guns to the left and the supports in a counterclockwise direction as viewed in Fig. 4 it will be apparent that the roll 58 which is located adjacent to the partition 72 will be drawn from the track 68 whereupon it will seat in its recess 38 thereby locking the associated latch 52 in operative position. Subsequently the next short roll 60 is drawn from the track 70 into its recess 38 after which the latch 52 is cammed by its engagement with the partition 72 to hold the roll therein. Whereas the latches 52 act only to lock the short rolls 60 in their respective recesses it will be clear that the long roll between any pair of short rolls thus locked will also be held in its respective recess and consequently the plates 32 will move as a unit with the supports 16, 18 thereby maintaining the opening closed at all times.

In order effectively to seal the plates 32 to the side walls 12 of the airplane, sealing members shown most clearly in Fig. 3 are provided. These each comprise a strip 76 of suitable material carried by upper and lower supporting arms 78 only one of which is illustrated, these supporting arms being pivoted about pins 80 on brackets 82 secured to the walls 12 of the airplane. Springs 84 urge the sealing strip 76 into engagement with the plates 32 but will yield outwardly to permit passage of the hinged portions of the plates thereby. The side wall 12 and the sealing member carried thereby have been eliminated in Fig. 1 to afford better illustration of the shield.

A guard 86 covers the rim of the support 18 between walls 50 to eliminate the possibility of danger to the operator by contact with the re-

cessed portion of the rim as the guns are moved in azimuth.

From the above it will be seen that the shield permits movements of the guns both in azimuth and in elevation throughout a wide range while maintaining the opening around the guns closed at all times. This is effected without in any way at any time obstructing the space rearwardly of the guns between the walls 50 of the compartments into which the excess plates of the shield are received.

Having thus described the invention what I claim as new and desire to secure by Letters Patent of the United States is:

1. An airplane gun mount comprising a pair of vertically spaced circular supports mounted for limited turning movements about a vertical axis, said supports providing between them an opening, a gun carried between said supports for movement therewith in azimuth and projecting through said opening, a flexible shield for that portion of the opening traversed by the gun, said shield comprising a plurality of narrow, vertically-extending plates, pintles pivoting said plates together about axes parallel to the axis of turning movement of the supports, pins carried by said pintles extending beyond the ends of said plates, rolls carried by said pins and received in recesses in the periphery of said supports, means for locking a predetermined number of said rolls in said recesses, and means operative upon turning said supports for guiding said rolls away from said supports at that side of the shield toward which said gun is moved in azimuth and for causing said plates to assume a folded relation.

2. A flexible gun shield comprising a plurality of long, narrow plates, pintles pivotally connecting said plates together, pins carried by said pintles extending beyond the ends of said plates, rolls carried by said pins, a rotatable support for said shield, means at opposite sides of said support for receiving the plates of said shield in folded relation, said support having recesses in its periphery for receiving said rolls, and means operative upon turning said support for successively separating the rolls from the support and folding the plates in said receiving means.

3. A flexible gun shield comprising a plurality of long, narrow plates, pintles pivotally connecting said plates together, pins carried by said pintles extending beyond the ends of said plates, rolls carried by said pins, a rotatable support for said shield, means at opposite sides of said support for receiving the plates of said shield in folded relation, said support having recesses in its periphery for receiving said rolls, means operative upon turning said support for successively separating the rolls from the support and folding the plates in said receiving means, and means for locking said rolls in said recesses until they have been moved into a predetermined position by said support.

4. A flexible gun shield comprising a plurality of long, narrow plates, pintles pivotally connecting said plates together, pins carried by said pintles extending beyond the ends of said plates, rolls carried by said pins, a rotatable support for said shield, means at opposite sides of said support for receiving the plates of said shield in

folded relation, said support having recesses in its periphery for receiving said rolls, said rolls being alternately long and short, a deep track arranged to guide the long rolls from the support to the receiving means, and a shallow track arranged to guide the short rolls from the support to the receiving means, said shallow track being spaced from the deep track whereby the plates are folded in the receiving means.

5. A flexible gun shield comprising a plurality of long, narrow plates, pintles pivotally connecting said plates together, pins carried by said pintles extending beyond the ends of said plates, rolls carried by the said pins, a rotatable support for said shield, means at opposite sides of said support for receiving the plates of said shield in folded relation, said support having recesses in its periphery for receiving said rolls, said rolls being alternately long and short, a deep track arranged to guide the long rolls from the support to the receiving means, a shallow track arranged to guide the short rolls from the support to the receiving means, said shallow track being spaced from the deep track whereby the plates are folded in the receiving means, and means for preventing the short rolls from entering said deep track.

6. A flexible gun shield comprising a plurality of long, narrow plates, pintles pivotally connecting said plates together, pins carried by said pintles extending beyond the ends of said plates, rolls carried by said pins, a rotatable support for said shield, means at opposite sides of said support for receiving the plates of said shield in folded relation, said support having recesses in its periphery for receiving said rolls, said rolls being alternately long and short, a deep track arranged to guide the long rolls from the support to the receiving means, a shallow track arranged to guide the short rolls from the support to the receiving means, said shallow track being spaced from the deep track whereby the plates are folded in the receiving means, and means for preventing the short rolls from entering said deep track, said means including latches arranged to lock each of the short rolls in the support until each short roll has moved beyond the entrance to the deep track.
